COIN CONTROLLED PRINTING AND
VENDING SCALEFred L. Mills, Oak Park, Ill., assignor to Mills
Novelty Company, Chicago, Ill., a corporation
of Illinois

Application August 15, 1931, Serial No. 557,296

19 Claims. (Cl. 194—21)

This invention relates to a coin-controlled weighing scale of the type having a printing mechanism which co-operates with the weighing mechanism of the scale to give a permanent printed record of the weight of the operator.

An important object of the invention is to provide, in combination with the weighing and printing mechanism of the scale, a vending mechanism which co-operates with the printing mechanism to deliver to the customer a piece of merchandise, such as a stick of gum or the like, the wrapper of which serves as a record slip or card upon which the weight of the customer is printed.

Another object of the invention is to provide in a scale of the type referred to a combined printing and vending mechanism which may be operated by the customer through a manually controlled member to obtain a printed record of his weight on the wrapper of the piece of merchandise vended.

Further objects and advantages of the invention will be apparent from the following detailed description, which, taken in connection with the accompanying drawings, discloses a preferred embodiment thereof.

Referring to the drawings:

Fig. 1 is a front elevational view of a scale embodying the invention;

Fig. 2 is a side elevational view thereof, a portion of the casing being broken away to show the internal structure;

Fig. 3 is a rear elevational view of the weighing and printing mechanism taken on line 3—3 of Fig. 2;

Fig. 4 is a broken rear elevational view showing the printing and vending mechanism on an enlarged scale;

Fig. 5 is a horizontal sectional view taken on line 5—5 of Fig. 4;

Fig. 6 is a vertical section showing the relation between the gum storage compartments and the printing wheel;

Fig. 7 is a front-to-back vertical section through the upper portion of the scale, the view being taken on line 7—7 of Fig. 4;

Fig. 8 is a front-to-back vertical section through the upper portion of the scale taken on line 8—8 of Fig. 4;

Fig. 9 is a fragmentary elevational view of the means for releasing the printed gum stick; and

Fig. 10 is a detail elevational view showing the cam means for actuating the stick transfer mechanism.

Briefly stated, the invention contemplates the combination in a scale of a printing mechanism

consisting of a printing wheel which is brought to the proper position by the weighing mechanism of the scale, together with a vending mechanism having compartments for holding a supply of gum sticks which are wrapped in the usual manner to provide a surface for receiving from the printing wheel an impression indicating the weight of the operator. Manually operable means, which is coin-controlled, is provided for bringing a gum stick into printing position on the printing wheel, said means then operating to print the figures indicating the weight of the operator upon the wrapper of the piece of gum. After printing is completed the manually operated control means releases the printed stick which then is delivered to a point from which it may be removed by the operator.

In the particular embodiment shown in the drawings the vending mechanism is designed for the handling of individual sticks of gum, upon the wrappers of which are printed the figures indicating the weight of the operator. It will be understood that other types of merchandise could be vended, such as pieces of candy and the like, which readily lend themselves to being wrapped in such form as to present a surface upon which the weight indicating numerals may be printed.

General views of the scale are shown in Figs. 1 and 2. The scale includes a base 11 in which is contained the weighing frame which supports a weighing platform 12. The base portion of the scale is not shown in detail, inasmuch as this portion is of well-known construction. The upright portion of the scale, indicated generally by the numeral 13, is supported on base 11 and contains the weighing mechanism and the printing and vending apparatus. This upright portion includes a housing consisting of a front wall 14, side walls 15, a rear wall 16, and a top wall 17. The rear wall 16, and the upper portion of front wall 14, are preferably made removable to permit of ready access to the interior of the scale. The housing walls are connected to suitable frame supports extending upwardly from the base, thereby providing a rigid frame unit for enclosing the scale mechanism.

The weighing mechanism of the scale will now be described in detail, reference for this purpose being had to Figs. 3, 4, and 7. This mechanism is mounted on a main supporting plate 18 which is secured along its opposite vertical edges to the side walls 15 of the housing. The weighing mechanism comprises: a weighing beam 19, which is fulcrumed at 21 on a block 22 carried by

plate 18; a pull rod 23, the upper end of which connects at 24 with beam 19 and the lower end of which connects with the weighing frame in the base; a printing wheel 25 mounted for free 5 rotation on a shaft 26; a cam segment 27, which is pivotally supported at 28 in a channel bracket 29 carried by the frame; and means affording an operative connection between segment 27 and the weighing beam, said means including a bracket 10 et 31 carried by beam 19, a lever 32 pivotally connected with bracket 31, and a roller arm 33 pivoted at one end in a bracket 34 which is supported on plate 18.

The weight of a person on the platform is 15 transmitted through rod 23 to weighing beam 19, this being resisted by a heavy coil spring 35 which is hung from plate 18 and which connects at its lower end through a hook 36 to the free end of beam 19. A dashpot 37, the piston 20 38 of which connects with the weighing beam, cushions the movement of the latter to prevent injury to the mechanism when a weight is suddenly placed on the platform.

Referring particularly to Fig. 7, shaft 26, which 25 carries printing wheel 25, is supported on plate 18, the forward end of said shaft being journaled in a bearing 39 mounted in said plate, and the rear end of said shaft being journaled in a bearing plate 41 which is carried by a bracket arm 30 42, the latter in turn being supported from plate 18. A pinion 43 is rigidly secured to shaft 26 and meshes with a toothed rack 44 which forms an integral part of cam segment 27. A fixed 35 relation between pinion 43 and the teeth on rack 44 is maintained by providing a pulley 45 on the rear end of shaft 26, said pulley having a weighted cord 46 depending therefrom which urges shaft 26 in a counter-clockwise direction, viewing Fig. 3, thereby avoiding play between 40 pinion 43 and rack 44. The hub of pulley 45 carries a projecting lip 47 which engages a similar lip 48 which projects from the hub of printing wheel 25. There is thus provided a connection 45 between shaft 26 and the printing wheel, whereby the latter is turned through the medium of rack 44 to bring it into printing position. A ribbon 49, secured to the periphery of the printing wheel, carries typed numerals which indicate the weight in pounds.

50 When there is no weight on the weighing platform, the printing wheel is so positioned that the zero number is at the top of the wheel. Cam segment 27 is over-balanced so that when weighing beam 19 is lowered, it will fall to impart the 55 required degree of rotation to printing wheel shaft 26. The lower portion of this segment carries a cam arm 51 which rests on a collar 52 carried by roller arm 33. A roller 53 carried on the free end of arm 33 engages the upper end of 60 lever 32, the latter being pivotally connected at 54 to bracket 51. One of the arms of bracket 31 carries an adjustable set screw 55 which engages a lip 56 carried by one of the arms of lever 32. A coil spring 57, extending between lever 32 and bracket 31, serves to hold lip 56 against the lower 65 end of set-screw 55. An adjustable connection is thus provided between lever 32 and bracket 31 whereby the printing wheel may be set so that 70 its zero position is at the top of the wheel when no weight is on the platform. Cam arm 51, it will be noted, is formed separately from the main body of cam segment 27 so that it may be bent towards or away from the latter to obtain such 75 adjustment as is necessary to move the printing

wheel through equal distances for equal increments of weight.

Considering briefly the operation of the weighing mechanism: When the operator steps on the weighing platform his weight lowers weighing beam 19 through the medium of rod 23, this movement being resisted by spring 35. The movement thus imparted to the weighing beam is transmitted through bracket 31 and lever 32 to roller arm 33. The movement of roller arm 33 10 is transmitted to cam segment 27 which falls under its own weight to produce rotation of printing wheel shaft 26. This falling or following-up movement of cam segment 27 is assisted by weighted cord 46. The turning of shaft 26 is im- 15 imparted through lips 47 and 48 to the printing wheel which is thus turned in a counter-clockwise direction, viewing Fig. 3, an amount sufficient to bring the number representing the weight of the person into printing position at the top 20 of the wheel.

In order to avoid damage to the parts by sudden shock, a spring connection (not shown) is provided between the hub of pulley 45 and the hub of printing wheel 25 so that said wheel, instead of stopping suddenly at the proper mark, will over-run slightly and then oscillate gradually back to its proper position under the action of weighted cord 46. A dial 58, carried on the forward end of printing wheel shaft 26, may be 30 viewed by the operator and serves to indicate when the printing wheel has come to a position of rest. As will presently appear, the printing and vending mechanisms are coin-controlled, being arranged to operate after a coin is introduced 35 through a coin slot 59 (Fig. 1). When the dial 58 has come to rest an accurate weighing may be obtained. If the coin is introduced before the printing wheel has come to rest at its proper position, the correct weight will, of course, not 40 be given.

The weight of the operator is recorded on the wrapper of a stick of gum which is dispensed with each weighing made. The mechanism which brings the stick of gum into position for printing 45 will now be described, reference being had to Figs. 4-7. A plate 61, which affords a support for the printing and vending mechanism, is secured at its lower end by bolts 62 to a cross-bar 63 which extends between the side walls of the housing. A 50 bed plate 64 extends forwardly from plate 61 adjacent the top of printing wheel 25. Extending upwardly from either side of this plate are a pair of gum storage magazines or compartments 65 and 66. These compartments may be made of 55 sheet metal which may be bent to form a channel-shaped container, the outer face of which is partially open to permit of ready access to the sticks contained therein. The magazines are secured at their rear edges to a plate 67 which in turn is 60 bolted to the main supporting plate 61. A reciprocating shifter or transfer plate 68 is interposed between the lower ends of the gum compartments and the upper face of plate 64, the forward edge of the latter being bent inwardly, as indicated at 65 69, to provide a guide for plate 68. Plate 68 is provided with a pair of rectangular openings 71 and 72 which alternately come into registry with the lower ends of the magazines 65 and 66, respectively, when plate 68 is at the end of its 70 stroke.

The sticks of gum indicated at 73 are stacked in the magazine holders, being so arranged therein that when one of the openings in plate 68 is moved beneath the magazine the lowermost stick will 75

fall into said opening. This is shown in Fig. 6, wherein the lowermost stick of the series has fallen into opening 72 in shifter plate 68. As plate 68 is shifted to the left, viewing Figs. 5 and 6, 5 by means presently to be described, the piece of gum in opening 72 is moved over an opening 74 in plate 64, this opening being positioned directly opposite the top of printing wheel 25. As the stick falls into opening 74 it rests on a type ribbon 75 10 which extends over the top of the printing wheel between a storage spool 76 and a take-up spool 77, the latter being mounted, respectively, on shafts 78 and 79 which are journaled in main supporting plate 61. It will be apparent that when shifter 15 plate 68 is moved to the left, viewing Fig. 6, opening 72 will move into registration with opening 74 in bed plate 64 and at the same time opening 71 will be moved beneath magazine 65 to receive the lowermost stick therein. This shifting of the 20 sticks is repeated in the reverse direction when shifter plate 68 moves to the right. The sticks are thus alternately transferred from one and then from the other of the storage compartments into position for printing on wheel 25.

Manually operable means is provided for actuating plate 68 to effect transfer of the sticks from the storage magazines into printing position on wheel 25. This mechanism is shown in elevation in Fig. 4 and in top plan in Fig. 5. It comprises: 25 a shaft 81, mounted for free rotation in a pair of lugs 82 and 83 projecting rearwardly from plate 61; a link 84 having pin and slot connection at 85 with shifter plate 68, and pivotally connected at 86 to a bracket 87 projecting rearwardly from plate 61; a pair of cam studs 88 and 89 mounted, respectively, on collars 91 and 92, which are secured to shaft 81; and a forked cam plate 93 mounted on link 84 and having arms 94 and 95 for engaging, respectively, with cam studs 88 and 40 89.

As shown in Fig. 10, cam studs 88 and 89 are positioned at 180° relative to one another on shaft 81, so that when the latter is turned through a half revolution in a counter-clockwise direction, 45 viewing Fig. 10, stud 89 will sweep over cam arm 95 to shift link 84 to the left, viewing Fig. 5. The movement of shifter plate 68 thus effected is sufficient to move one of the sticks from magazine 66 into printing position over the printing wheel. 50 Similarly, when shaft 81 is advanced another half revolution, cam stud 88 engages cam arm 94 to move shifter plate 68 in the reverse direction, this movement serving to transfer one of the sticks from magazine 65 into printing position at the 55 top of the printing wheel. A stick is thus brought into printing position each time shaft 81 is turned through 180°.

One end of shaft 81 projects through a side wall 15 to receive a hand piece 96 which is rigidly secured thereto and which is grasped by the operator standing on the platform to operate the vending mechanism.

The printing mechanism, which is also operated through hand piece 96 and shaft 81 will now be described, reference being had to Fig. 7. The printing mechanism consists of an impression hammer 97 which is suspended by a coil spring 98 from a bracket 99, the latter in turn being supported on plate 61. An actuating arm 101, pivoted at 102 to a lug 103 (Fig. 5) projecting rearwardly from plate 61, extends through a slot or opening in hammer 97 and has a lost play connection with said hammer through the medium of a pin 104 which is carried in the end of arm 101 75 and which extends through elongated slots 105

formed in the sides of hammer 97. A pair of coil springs 106 (Figs. 5 and 7), extending between the upper end of the hammer and the projecting ends of pin 104, afford a yielding connection between the forward end of arm 101 and hammer 97. 5

Continuing the reference to Fig. 7, the impression hammer is shifted from the inactive position shown by the solid lines to active printing position, represented by the dotted lines, by means of a pair of cam studs 107 carried by a collar 108 which 10 is rigidly secured to shaft 81. These cam studs are positioned at 180° relative to one another and are arranged to strike a shouldered surface portion 109 of arm 101 to force the latter downwardly, which in turn shifts the impression hammer to 15 printing position, this being clearly shown in Fig. 7. It will be evident that each time shaft 81 is turned through a half revolution one or the other of studs 107 will strike arm 101 to actuate the hammer. As arm 101 moves to horizontal position, stud 107 rides over the shouldered portion 109 to allow the impression hammer and arm 101 to be lifted to inactive position by spring 98. It may be added that cam studs 107 are so positioned on shaft 81 relative to studs 88 and 89 that they 20 do not actuate arm 101, and in turn the impression hammer, until shifter plate 68 has been moved to bring the stick into printing position. 25

Release means is provided for dropping a printed stick from printing wheel 25 upon completion of the printing operation. This means, which is also operated from the manually-controlled shaft 81, is shown in Figs. 5 and 9. It comprises: an arm rest 111, pivoted at 112 to the under face of bed plate 64; a lever 113, fulcrumed 30 at 114 on a bracket 115 projecting rearwardly from plate 61; a link 116 extending between one end of arm rest 111 and the lower end of lever 113; and a pair of cam projections 117 formed on a collar 118 which is rigid on shaft 81. A coil 35 spring 119 extending between arm rest 111 and a fixed point on bed plate 64 normally holds said rest in the position shown in Fig. 5, so that its free end 121 extends under the forward end of opening 74 in bed plate 64. In this position, portion 121 of the rest engages and supports the forward end of the gum stick which rests in printing position on wheel 25. Upon completion of the printing operation one of the cam projections 117 40 strikes the end of lever 113 which in turn pivots 45 to draw link 116 rearwardly. This movement of link 116 pivots arm rest 111 in a counter-clockwise direction, viewing Fig. 5, sufficiently to remove the portion 121 from beneath the forward end of the gum stick. Since the major portion of 50 the stick extends forwardly from printing wheel 25, it is greatly over-balanced upon removal of arm rest 111 and immediately gravitates into a tray 122 which is supported in and extends through front wall 14, an opening 123 being provided therein through which the stick may be removed by the operator. Cam projections 117 are 55 so positioned on shaft 81 that they will actuate the release means immediately after the printing of the stick has been effected. 60

The vending, printing, and release mechanisms, all of which pass through a complete cycle of operations for each half revolution of shaft 81, 65 are arranged to be coin-controlled through the provision of a coin-operated latch which controls the rotation of shaft 81. This latch mechanism includes means for applying a brake to the printing wheel to hold it in proper position for printing, together with a latch device for controlling the rotation of shaft 81. This mechanism is shown 70 75

in Figs. 4, 7, and 8. It comprises: a stop wheel 124, rigid on shaft 81 and provided with diametrically opposed stop lugs 125; a latch lever 126 which is pivoted at 127 to a frame piece 128 supported from plate 61; a brake arm 129 pivoted at 131 to a frame piece supported by plate 61; and a latch 132, pivoted at 133 to frame piece 128.

Brake arm 129 is forked or bifurcated at its forward end to provide a pair of fingers 134 (Fig. 6) having a rubber covering 135 around their tips for engaging the inner brim portion of printing wheel 25. The other end of this brake arm is shouldered at 136, the arm terminating in a narrow projection 137 which engages a rearwardly projecting lip 138, the latter forming an integral part of latch lever 126. The shoulder 136 on brake arm 129 normally rests in a notch 139 (Fig. 4) which is formed in the upper end of an arm carried by coin latch 132. A coil spring 142, connected at its lower end to coin latch 132, and at its upper end to latch lever 126, normally holds the parts in the position shown by solid lines in Fig. 4. In this position of the parts, the upper end of latch lever 126 engages one of the stop lugs 125 to prevent rotation of shaft 81. Reverse rotation of this shaft is prevented by a pawl arm 143 which is held in engagement with the teeth of wheel 124 by a coil spring 144.

When a coin is inserted through coin slot 59, it is directed by a coin chute (not shown) onto a rod 145 carried by coin latch 132. The weight of the coin shifts latch 132 into the position shown by the dotted lines in Fig. 4, thereby releasing brake arm 129, which is immediately pivoted into the braking position indicated in dotted lines in Fig. 7 by a coil spring 146, which extends between said arm and bar 63, and which tends to pivot the arm in a counter-clockwise direction, viewing Fig. 7. The printing wheel is thus held against rotation by brake arm 129 during the printing operation. As soon as brake arm 129 pivots into braking position, latch lever 126 is free to be pivoted by spring 142 in a counter-clockwise direction to the position indicated by the dotted lines in Fig. 4, this movement serving to free stop wheel 124 to permit rotation of shaft 81.

The parts remain in the position shown by the dotted lines in Fig. 4 until shaft 81 approaches the end of a half turn, at which time an adjustable set screw 147, carried on the lower end of the hammer-actuating arm 101, moves upwardly, as indicated in Fig. 7, to strike against a set-screw 148 which projects laterally from brake arm 129. The latter is thus raised against the tension of spring 146 sufficiently to fall back into latched position on shoulder 139. This movement of brake arm 129 in turn pivots latch lever 126 into position to engage one of the stop lugs 125, this movement being effected by reason of the engagement between parts 137 and 138. The coin latch and brake mechanism is thus restored to its initial position after having allowed a half revolution of shaft 81.

Referring to Fig. 6, the type ribbon 15 is wound up on take-up spool 77 a slight amount each time plate 68 is moved to the right. This is effected by a leaf spring 149 which depends from the under surface of plate 68 and which engages teeth 151 on spool 77 to turn the latter a slight amount each time plate 68 moves to the right. When plate 68 is positioned to the left far enough to allow spring 149 to clear teeth 151, the ribbon may be re-wound on spool 76 by turning a finger piece 152 (Fig. 5) carried on shaft 78.

It is believed that a brief statement of the se-

quence of operation of the various parts of the vending, printing, and release means will aid to a clearer understanding of the invention. Assuming that the operator has stepped on the platform and that printing wheel 25 has come to rest with the number representing the weight of the person at the top of the wheel, this being indicated by the fact that the dial 58 no longer oscillates, the operator inserts a coin in coin slot 59. As the coin strikes rod 145 (Fig. 4) latch 132 is freed from brake arm 129, which immediately clamps the printing wheel in printing position, and at the same time latch lever 126 is moved clear of stop wheel 124. The operator then grasps hand piece 96 and proceeds to turn it in a counter-clockwise direction, viewing Fig. 7. As shaft 81 is turned, cam stud 89 (Fig. 5) moves upwardly on cam plate 95 to shift plate 68 to the left, the result of this operation being to transpose the lowermost stick in magazine 66 to printing position in the opening 74 in bed plate 64. Immediately upon the positioning of the stick on the printing wheel, printing is effected by engagement of one of the cam studs 107 (Fig. 7) with shoulder portion 109 on arm 101, the latter being thus lowered to move impression hammer 91 against the stick which lies in opening 74 on the top of the printing wheel. The lowering of arm 101 serves to re-set latch lever 126 by reason of the engagement between set-screw 147, carried on the lower end of arm 101, and screw 148 carried by brake arm 129. Latch lever 126 being thus returned to obstructing position, will engage the succeeding stop 125 when a half revolution of shaft 81 has been completed.

Referring particularly to Fig. 7, as soon as shaft 81 has been turned far enough to cause stud 107 to clear shoulder portion 109, the impression hammer is lifted to inactive position by spring 98. As soon as the impression hammer is thus removed the stick is released by the shifting of arm rest 111 from beneath the forward end thereof, this being effected by engagement of one of the cam projections 147 (Fig. 9) with lever 113, the latter connecting through link 116 with arm rest 111. The printed stick then falls into tray 122 where it may be removed by the operator.

The mechanism thus provides means for vending an article of merchandise each time a weighing is made, at the same time giving the operator a printed record of his weight on the wrapper of the merchandise which he obtains. The construction of the vending and printing mechanism is greatly simplified by reason of the fact that the mechanism is arranged to be manually operated. Shaft 81, which is turned by hand piece 96, carries the various cams which operate the different portions of the printing, vending, and release mechanisms. There is little chance of faulty operation since a minimum of parts is employed and since the movements of the several parts are accurately timed relative to one another through shaft 81.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. In a weight printing and vending scale, the combination of: printing mechanism including an impression hammer, a printing wheel, and means operated by the weighing mechanism of

the scale for positioning said wheel; vending mechanism comprising a container for holding a supply of articles of merchandise, the latter being wrapped to provide a surface for receiving a printed impression of the weight, and means for transferring the articles from said container into printing position between said wheel and the impression hammer; and coin-controlled means for operating said transfer means and subsequently actuating the impression hammer.

2. In a weight printing and vending scale, the combination of: printing mechanism including an impression hammer, a printing wheel, and means operated by the weighing mechanism of the scale for positioning said wheel; vending mechanism comprising a container for holding a supply of articles of merchandise, the latter being wrapped to provide a surface for receiving a printed impression of the weight, and means for transferring the articles from said container into printing position between said wheel and the impression hammer; and coin-controlled means including a shaft and a member whereby the same may be manually rotated for operating said transfer means and subsequently actuating the impression hammer.

3. In a weight printing and vending scale, the combination of: printing mechanism including an impression hammer, a printing wheel, and means operated by the weighing mechanism of the scale for positioning said wheel; vending mechanism comprising a container for holding a supply of articles of merchandise, the latter being wrapped to provide a surface for receiving a printed impression of the weight, and means for transferring the articles from said container into printing position between said wheel and the impression hammer; release means including a movable support for holding the article adjacent the wheel during the interval of printing; and coin-controlled means for operating said transfer means and subsequently actuating the impression hammer and said release means.

4. In a weight printing and vending scale, the combination of: printing mechanism including an impression hammer, a printing wheel, and means operated by the weighing mechanism of the scale for positioning said wheel; vending mechanism comprising a container for holding a supply of articles of merchandise, the latter being wrapped to provide a surface for receiving a printed impression of the weight, and means for transferring the articles from said container into printing position between said wheel and the impression hammer; release means including a movable support for holding the article adjacent the wheel during the interval of printing; and coin-controlled means including a shaft and a member whereby the same may be manually rotated for operating said transfer means and subsequently actuating the impression hammer and said release means.

5. In a weight printing and vending scale, the combination of: a weighing platform; a printing wheel; means operated by movement of the platform for positioning said wheel; an impression hammer disposed adjacent the wheel; a container for holding a supply of articles of merchandise disposed adjacent the wheel on either side of the impression hammer, said articles being wrapped to provide a surface for receiving a printed impression of the weight; means for alternately transferring an article from one and then from the other of said containers into printing position between said wheel and the impression hammer; and a coin-controlled manually

and coin-controlled means for operating said transfer means and subsequently actuating the impression hammer.

6. In a weight printing and vending scale, the combination of: a weighing platform; a printing wheel; means operated by movement of the platform for positioning said wheel; an impression hammer disposed adjacent the wheel; a container for holding a supply of articles of merchandise disposed adjacent the wheel on either side of the impression hammer, said articles being wrapped to provide a surface for receiving a printed impression of the weight; means for alternately transferring an article from one and then from the other of said containers into printing position between said wheel and the impression hammer; release means including a movable support for holding the article adjacent the wheel during the interval of printing; and coin-controlled means for operating said transfer means and subsequently actuating the impression hammer and said release means.

7. In a weight printing and vending scale, the combination of: a weighing platform; a printing wheel; means operated by movement of the platform for positioning said wheel; an impression hammer disposed adjacent the wheel; a storage container for articles of merchandise disposed adjacent the wheel on either side of the impression hammer; a bed plate positioned between the wheel and the hammer and having an opening therein opposite the hammer; a shifter plate movably supported between said bed plate and the discharge ends of said containers, said plate having openings therein for receiving the articles; means for actuating said shifter plate to alternately transfer an article from one and then from the other of said containers into printing position between said hammer and the printing wheel; and coin-controlled means for operating said plate actuating means and subsequently actuating the impression hammer.

8. In a weight printing and vending scale, the combination of: a weighing platform; a printing wheel; means operated by movement of the platform for positioning said wheel; an impression hammer disposed adjacent the wheel; a storage container for articles of merchandise disposed adjacent the wheel on either side of the impression hammer; a bed plate positioned between the wheel and the hammer and having an opening therein opposite the hammer; a shifter plate movably supported between said bed plate and the discharge ends of said containers, said plate having openings therein for receiving the articles; means for actuating said shifter plate to alternately transfer an article from one and then from the other of said containers into printing position between said hammer and the printing wheel; and a coin-controlled manually rotatable shaft having cam means thereon for operating said transfer means and subsequently actuating the impression hammer.

9. In a weight printing and vending scale, the combination of: printing mechanism including an impression hammer, a printing wheel, and means operated by the weighing mechanism of the scale for positioning said wheel; vending mechanism comprising a container for holding a supply of articles of merchandise, the latter being wrapped to provide a surface for receiving a printed impression of the weight, and means for transferring the articles from said container into printing position between said wheel and the impression hammer; and a coin-controlled manually

rotatable shaft having cam means thereon for operating said transfer means and subsequently actuating the impression hammer.

10. In a weight printing and vending scale, 5 the combination of: printing mechanism including an impression hammer, a printing wheel, and means operated by the weighing mechanism of the scale for positioning said wheel; vending mechanism comprising a container for holding 10 a supply of articles of merchandise, the latter being wrapped to provide a surface for receiving a printed impression of the weight, and means for transferring the articles from said container into printing position between said 15 wheel and the impression hammer; manually operable means for operating said transfer means and subsequently actuating the impression hammer; and a latch device adapted to be actuated by a coin to permit actuation of said 20 manually operable means.

11. In a weight printing and vending scale, the combination of: a weighing platform; a printing wheel; means operated by movement of the platform for positioning said wheel; an impression 25 hammer disposed adjacent the wheel; vending mechanism comprising a container for holding a supply of articles of merchandise, the latter being wrapped to provide a surface for receiving a printed impression of the weight, and 30 means for transferring the articles from said container into printing position between said wheel and the impression hammer; a manually rotatable shaft having cam means thereon for operating said transfer means and subsequently 35 actuating the impression hammer; and a latch device adapted to be actuated by a coin to permit actuation of said manually-operable means.

12. In a weight printing and vending scale, the combination of: a weighing platform; a printing 40 wheel; means operated by movement of the platform for positioning said wheel; an impression hammer disposed adjacent the wheel; vending mechanism comprising a container for holding a supply of articles of merchandise, the latter being wrapped to provide a surface for receiving a printed impression of the weight, and 45 means for transferring the articles from said container into printing position between said wheel and the impression hammer; a manually rotatable shaft having cam means thereon for operating said transfer means and subsequently 50 actuating the impression hammer; and coin-controlled means for regulating rotation of said shaft comprising a stop member rotatable with 55 said shaft, a latch for engaging said stop member to prevent rotation of the shaft, and a coin-operated release member for moving said latch to non-obstructing position.

13. In a weight printing and vending scale, the 60 combination of: a weighing platform; a printing wheel; means operated by movement of the platform for positioning said wheel; an impression hammer disposed adjacent the wheel; vending mechanism comprising a container for holding a supply of articles of merchandise, the latter being wrapped to provide a surface for receiving a printed impression of the weight, and 65 means for transferring the articles from said container into printing position between said 70 wheel and the impression hammer; release means including a movable support for holding the article adjacent the wheel during the interval of printing; a manually rotatable shaft having cam means thereon for operating said transfer means 75 and subsequently actuating the impression ham-

mer and said release means; and a latch device adapted to be actuated by a coin to permit rotation of said shaft.

14. In a weight printing and vending scale, the combination of: a weighing platform; a printing 5 wheel; means operated by movement of the platform for positioning said wheel; an impression hammer disposed adjacent the wheel; vending mechanism comprising a container for holding a supply of articles of merchandise, the latter 10 being wrapped to provide a surface for receiving a printed impression of the weight, and means for transferring the articles from said container into printing position between said wheel and the impression hammer; release 15 means including a movable support for holding the article adjacent the wheel during the interval of printing; a manually rotatable shaft having cam means thereon for operating said transfer means and subsequently actuating the 20 impression hammer and said release means; a latch device adapted to be actuated by a coin to permit rotation of said shaft; and brake means for engaging the printing wheel to hold the latter against rotation during the interval of 25 printing.

15. In a weight printing and vending scale, the combination of: a weighing platform; a printing wheel; means operated by movement of the platform for positioning said wheel; an impression 30 hammer disposed adjacent the wheel; vending mechanism comprising a container for holding a supply of articles of merchandise, the latter being wrapped to provide a surface for receiving a printed impression of the weight, and means for 35 transferring the articles from said container into printing position between said wheel and the impression hammer; manually operable means for operating said transfer means and subsequently 40 actuating the impression hammer; a latch device adapted to be actuated by a coin to permit actuation of said manually operable means; and brake means for engaging the printing wheel to hold the latter in fixed position during the interval of printing, said means having operative 45 connection with said coin-operable latch whereby operation of the latter throws said brake means to operative position against the wheel.

16. In a weight printing and vending scale, the combination of: a weighing platform; a printing 50 wheel; means operated by movement of the platform for positioning said wheel; an impression hammer disposed adjacent the wheel; vending mechanism comprising a container for holding a supply of articles of merchandise, the latter being wrapped to provide a surface for receiving a printed impression of the weight, and means for 55 transferring the articles from said container into printing position between said wheel and the impression hammer; release means including a movable support for holding the article against the wheel during the interval of printing; coin-controlled means for operating said transfer means and subsequently actuating the impression hammer and said release means; and brake means 60 for engaging the printing wheel to hold the latter against rotation during the interval of printing.

17. In a coin-controlled weighing and vending machine, the combination of a magazine adapted to contain a quantity of wrapped articles 65 to be vended, a scale, printing mechanism controlled by said scale to cause the weight of a person being weighed to be printed on the wrapper of an article delivered from said magazine, said printing mechanism including an impression 70

hammer, and coin-controlled means for actuating said impression hammer, said means including an actuating member provided with means whereby the same may be manually operated to effect positive actuation of said coin-controlled means.

18. In a coin-controlled weighing and vending machine, the combination of a magazine adapted to contain a quantity of wrapped articles to be vended, weighing mechanism, printing mechanism, and coin-controlled means for transferring said wrapped articles from said magazine to a printing station and for subsequently actuating said printing mechanism, said means including an actuating member provided with means whereby the same may be manually operated to effect positive actuation of said coin-controlled means, and said printing mechanism including an element operable by the weighing

mechanism for causing the weight of a person being weighed by the latter to be printed upon the wrapper of said article.

19. In a coin-controlled weighing and vending machine, the combination of a magazine adapted to contain a quantity of wrapped articles to be vended, weighing mechanism, printing mechanism, and a coin-controlled shaft provided with a member permitting manual rotation thereof, said shaft having means thereon, operative upon rotation of the shaft, for transferring said wrapped articles from said magazine to a printing station and for actuating said printing mechanism, and said printing mechanism including an element operable by the weighing mechanism for causing the weight of a person being weighed by the latter to be printed upon the wrapper of said article.

FRED L. MILLS.
